FRUIT LOADING HOPPER FOR A HARVESTING MACHINE

Dietrich G. Rempel, Akron, Ohio, assignor to
Rempel Enterprises, Inc., Akron, Ohio

Filed Feb. 3, 1975, Ser. No. 546,438

Term of patent 14 years

Int. Cl. D15—03

U.S. Cl. D40—1 R

FIG. 1

FIG. 2

FIG. 3

FIG. 4

FIG. 1 is a top plan view of a fruit loading hopper for a harvesting machine embodying my new design.

FIG. 2 is a side elevational view thereof, the opposite side being a mirror image of the side shown herein.

FIG. 3 is a rear elevational view thereof, taken along the line 3—3 of FIG. 2.

FIG. 4 is a bottom plan view thereof.

I claim:

The ornamental design for a fruit loading hopper for a harvesting machine, as shown and described.
